UNITED STATES PATENT OFFICE.

PLEASANT T. REED, OF ANDERSON, INDIANA, ASSIGNOR TO THE WARD-STILSON COMPANY, OF ANDERSON, INDIANA, A CORPORATION.

DESIGN FOR A PENNANT.

51,079.

Specification for Design. **Patented July 24, 1917.**

Application filed April 30, 1917. Serial No. 165,627. Term of patent 3½ years.

To all whom it may concern:

Be it known that I, PLEASANT T. REED, a citizen of the United States of America, residing in the city of Anderson, in the county of Madison and State of Indiana, have invented a new and original and ornamental Design for a Pennant, of which the following is a specification, reference being had

to the accompanying drawing, forming a part thereof.

The figure is an elevation of a pennant illustrating my new design.

I claim:

The ornamental design for a pennant, as shown.

PLEASANT T. REED.
